CORELESS INDUCTION HEATER

Bela Ronay, Annapolis, Md.

Application December 14, 1938, Serial No. 245,648
2 Claims. (Cl. 219—47)(Granted under the act of March 3, 1883, as
amended April 30, 1928; 370 O. G. 757)

This invention relates to coreless induction heaters, and it has a particular relation to heaters for annealing and preheating pipe joints and the like.

5 The principal object of the present invention is the provision of a coreless induction heater which is simple, inexpensive and efficient in construction and operation and which may quickly and easily be assembled around a pipe joint or the like being heated, welded or annealed.

With these and other objects in view, as well as other advantages that may be incident to the use of the improvements, the invention consists in the parts and combinations thereof hereinafter 15 set forth and claimed, with the understanding that the several necessary elements constituting the same may be varied in proportion and arrangement without departing from the nature and scope of the invention, as defined in the appended claims.

20 In order to make the invention more clearly understood, there are shown in the accompanying drawing, means for carrying the invention into practical use, without limiting the improvements in their useful application to the particular construction, which, for the purpose of explanation, have been made the subject of illustration.

25 In the accompanying drawing:
30 Fig. 1 is an end elevational view of a coreless heater embodying the invention;

Fig. 2 is a plan view of the structure shown in Fig. 1; and

35 Fig. 3 is a fragmentary sectional view through one of the tie-rods.

Referring to the drawing, a coreless induction heater constructed in accordance with the invention is shown as comprising a plurality of conductors 10 of substantially U-shape and having vertically extending legs 11 and 12 secured together by tie rods 13 and 14 in spaced parallel relation and together forming a group embracing a pipe 15 to be heated. The legs 11 and 12 of the conductors 10 on opposite ends of the 40 group are formed with transversely extending portions or flanges 16 and 17, respectively, to which cables 18 and 19 are secured leading to the secondary windings of a power transformer. The conductors 10 are preferably constructed of 45 copper tubing flattened to a total thickness of three times that of the walls so as to provide an air duct therethrough for cooling purposes. The conductors 10 are insulated from the tie rods 13 and 14 by tubular members 20 (Fig. 3) and 50 from one another by spacing washers 21. The

end legs 11 of the conductors 10 are slotted to receive a plurality of connecting straps or bringing members 22. These straps are pivotally connected in the slots of the legs 11 of the conductors 10 and are offset angularly with respect to the 5 axis of the pipe 15 for frictional engagement with the slots in the legs 12 of the next adjacent conductor in the manner of a knife switch. In this manner the assembly or group is substantially the same as a helical coil in that electric 10 current flows through the conductors 10 and straps 20 successively, so as to induce a current in the pipe 15, acting as a core, and heat the same.

The pipe 15 is properly centered by adjusting 15 screws 23 which are threaded into the rods 13 and 14 adjacent to the ends thereof. The pipe 15 may be surrounded with an asbestos packing 24, if desired. In the drawing, the pipe 15 is shown as having a drain line 25 welded therein 20 which is also included in the portion of the pipe being heated by not closing the strap 22 adjacent to the branch pipe. In this adaptation of the device the circuit is completed through the heater by means of a flexible jumper 26, one end of 25 which is fixed to a plate 27 which is inserted in the slotted end of the conductor on one side of the branch pipe and the other end of which may be attached to the strap 22 on the other side of 30 the pipe 25.

If it is desired to use the apparatus as a pre-heater, it may be set in position and with the blades open the joint may be tacked. The blades 22 are then closed and the current turned on to 35 preheat the pipe ends. When the desired preheat temperature is reached, the current may be cut off, the blades opened and the welding started at the portion bared by opening the blades. On completion of this portion of the weld, the centering screws may be loosened and the apparatus rotated to bare the adjacent quadrant. This 40 may be repeated until the entire weld is completed. Thereafter, the blades may be closed and the postheat treatment may begin taking ad- 45 vantage of the heat accumulation in the joint.

The fact that each turn is individually closed by a blade makes the apparatus suitable for use to preheat and postheat other than straight butt joints. In case a small diameter drain line 25 is 50 welded into a large diameter steam main 15, as shown in the drawing, the connection, because of the extreme localization of the weld, causes the development of residual stresses of a higher order. Such welds must be stress relieved; and if 55

the tube is of an air-hardening low alloy steel, the joint must be preheated.

It will be understood that the above description and accompanying drawing comprehend only the general and preferred embodiment of the invention, and that various other changes in the construction, proportion and arrangement of the parts may be made by those skilled in the art without departing from the nature and scope of the invention as defined in the appended claims.

10 The invention described herein may be manufactured and/or used by or for the Government of the United States of America for governmental purposes without the payment of any royalties thereon or therefor.

15 I claim:

1. A coreless induction heater for pipe joints and the like comprising a group of hollow conductors of substantially U-shape secured together 20 in spaced parallel relation and electrically insu-

lated from one another, and a plurality of straps pivotally connected to one leg of each of said conductors and offset angularly with respect thereto for electrical contact with the opposite leg of an adjacent conductor to complete an electric circuit through said group and to embrace a pipe being heated.

2. A coreless induction heater for pipe joints and the like comprising a group of flattened tubular conductors of substantially U-shape secured together in spaced parallel relation and electrically insulated from one another, a plurality of straps pivotally connected to one leg of each of said conductors and offset angularly with respect thereto for electrical contact with the opposite leg of an adjacent conductor to complete an electric circuit through said group and to embrace a pipe being heated, and means for positioning the pipe within said heater.

BELA RONAY. 20
